DESIGN FOR A COMBINED PICTURE FRAME AND CALENDAR HOLDER OR SIMILAR ARTICLE

Dmytro Stec, Dearborn, Mich.

Application May 2, 1947, Serial No. 138,771

Term of patent 7 years

(Cl. D29—20)

To all whom it may concern:

Be it known that I, Dmytro Stec, a citizen of the United States, residing at Dearborn, in the county of Wayne and State of Michigan, have invented a new, original, and ornamental Design for a Combined Picture Frame and Calendar Holder or Similar Article, of which the following is a specification, reference being had to the accompanying drawing, forming a part thereof.

Figure 1 is a front elevational view of a combined picture frame and calendar holder or similar article, showing my new design.

Figure 2 is a side view.

Figure 3 is a top plan view.

Figure 4 is a partial sectional view taken along the line 4—4 of Figure 1.

I claim:

The ornamental design for a combined picture frame and calendar holder or similar article, as shown.

DMYTRO STEC.
